GEAR PUMP

William F. Stoermer, Corry, Pa., assignor to Aero Supply Mfg. Co., Inc., Corry, Pa.

Application August 27, 1951, Serial No. 243,800

1 Claim. (Cl. 103—126)

This invention relates to gear pumps.

An object of this invention is to provide a pump embodying a plurality of intermeshing gears having a common driving gear with an improved port arrangement, whereby fluid will be admitted to and discharged from the gears.

Another object of this invention is to provide a gear pump which will have increased capacity over similar pumps at present available.

A further object of this invention is to provide a gear pump which is formed of a central plate having apertures therethrough in which the gears rotatably engage, an outer plate at one side of the central plate having one or more intake ports, and a second outer plate on the opposite side of the central plate having one or more outlet ports.

A further object of this invention is to provide a gear pump which is so constructed and arranged that it may be produced as a very compact pump structure.

A further object of this invention is to provide a gear pump structure embodying a central plate and outer plates on each side of the central plate, the latter being formed with a central opening in which a driving gear rotatably engages, and also two or more openings adjacent to and communicating with the central opening and in which the driven gears are journaled, the arrangement being such as to eliminate the necessity of any shafts or studs for the driven gears.

A further important object of the invention is to provide a gear pump embodying a driving gear and two or more driven gears wherein the driving gear is so related in diameter to the driven gears as to obtain from a unit of an overall fixed size a maximum of pumping capacity within a minimum size of unit, and whereby the capacity of a fixed size unit may be increased beyond what would be the normal therefor with only a conventional type arrangement of gears.

With the above and other objects in view, my invention consists in the arrangement, combination and details of construction disclosed in the drawings and specification, and then more particularly pointed out by the appended claim.

In the drawings—

Figure 1 is a detail front elevation of a pump constructed according to an embodiment of this invention,

Figure 2 is a detail side elevation of the pump,

Figure 3 is a sectional view taken on the line 3—3 of Figure 1,

Figure 4 is a fragmentary sectional view taken on the line 4—4 of Figure 3,

Figure 5 is a sectional view taken on the line 5—5 of Figure 3,

Figure 6 is a side elevation of the intake plate,

Figure 7 is an inner side elevation of the outer end of the housing,

Figure 8 is a detail side elevation of the outlet plate,

Figure 9 is a fragmentary sectional view taken on the line 9—9 of Figure 5,

2

Figure 10 is an inner side elevation of the inner end of the housing;

Figure 11 is an outer end elevation of the inner wall of the housing;

Figure 12 is a fragmentary sectional view taken on the line 12—12 of Figure 5.

Figures 13 to 16 are diagrammatic views of a series of modified forms of this invention.

Referring to the drawings, the numeral 15 designates generally a centrally disposed disc-shaped plate or body which is formed with a pair of oppositely disposed intake openings 19 and 20, and is also formed with a pair of oppositely disposed outlet openings 21 and 22. An inner disc-shaped plate 23 is disposed in face abutting relation to the inner side of the central plate or body 15, and is formed with a pair of oppositely disposed intake openings 24 and 25, adapted to register with the intake openings 19 and 20 of central plate or body 15.

An outer disc-shaped plate 26 is disposed in face abutting relation to the outer side of central plate or body 15, and is formed with a pair of oppositely disposed outlet ports or openings 27 and 28. The central opening 16 in body 15 is substantially larger in diameter than the openings 17 and 18, and a driving gear 29 is rotatably disposed in the opening 16. The driving gear 29 is formed with a polygonal bore 30, within which the polygonal portion 31 of a drive shaft 32 is adapted to engage.

A driven gear 33 is rotatably disposed within the opening 17 meshing with gear 29, and a second driven gear 34 is rotatably disposed in opening 18 and also meshes with central driving gear 29. The two smaller gears 33 and 34 are journaled within the openings 17 and 18 so that it will not be necessary to provide any pinions or stub shafts for these gears.

A housing generally designated as 35 encases the pump assembly, comprising the plate members 15, 23 and 26, and the gears 29, 33 and 34. The housing 35 comprises a substantially cylindrical body 36 engaging about the plates 15, 23 and 26, and an inner end wall 37 is carried by the cylindrical member 36. The inner wall 37, shown more clearly in Figures 10 and 11, is formed with an arcuate recess 38, and a pair of inwardly extending channels 39 and 40. The channel 39 communicates with a second channel 41 through a transverse opening 42, and channel 41 extends inwardly and communicates with intake opening 24 in plate 23. Intake channel 40 also communicates with a channel 43 through an opening 44, and channel 43 communicates with intake opening 25.

The inner end of the housing 35 includes an upwardly projecting plate 45 which is adapted to be attached to one end of a power member which may be an engine or the like. The channels 39 and 40 open through the inner side of the inner wall 37, and a cover plate 46 is secured by fastening means 47 to the inner side of the end wall 37, and plate 46 provides a means whereby the liquid, such as oil or the like, will be drawn into the channels 39 and 40 through the recess or intake chamber 38.

The cylindrical body 36 is formed with an annular flange 48 at its outer end, and an outer end wall 49 is disposed within the body 36 and is formed with an annular flange 50 engaging within a counterbore 51 formed in the flange 48. A sealing gasket 52 is disposed within the counterbore 51 and provides a seal to prevent liquid from passing about the end wall 49.

The end wall 49 is secured to the inner end wall 37 by means of bolts 53 which extend through the outer wall 49, the plates 26, 15 and 23, and are threaded into the inner end wall 37. The inner side of the outer wall 49 is formed with an annular outlet channel 54, communicating with the outlet ports 27 and 28 in plate 26, and a radially extending channel is formed in wall 49, being

designated 55, and communicates with annular channel 54. The housing 35 has extending therefrom an outlet nipple 56 which communicates with a chamber 57 formed in the boss 58. The chamber 57 includes an inwardly extending chamber or channel 59 which communicates with radial channel 55. The nipple 56 is formed with right angularly disposed bosses 60 and 61 adjacent the outer end thereof so that the fluid may be taken off from the nipple 56 by a connection disposed coaxially with the nipple 56, or a connection extending at right angles thereto. It will, of course, be understood that the plug will be inserted into the unused boss 60 or 61.

In the use and operation of this pump, the shaft 32 is connected at its inner end to a driving means such as the drive shaft of an engine or other suitable driving means. As shown in Figure 3, the outer end of the shaft 32 is rotatably disposed in bearing sleeve or bushing 62 carried by the outer end wall 49, and a thrust ball 63 is disposed in a seat 64 formed in the outer end of the shaft 32 and bears against a thrust plate 65 countersunk in the plate or end wall 49. It will be understood that the gear pump which comprises the central plate 15 and the two plates 23 and 26, with the gears 29, 33 and 34, may be encased in any suitable housing. The housing hereinbefore described shows one specific form of housing which was particularly designed for a specific type of engine or power means.

With rotation of shaft 32, gears 29, 33 and 34 will be rotated therewith and fluid such as oil or the like will be drawn into chamber 38 and into the intake openings 24 and 25 of inner plate 23. The fluid will then be carried outwardly in the openings 17 and 18 and will be discharged from the valleys of the teeth of the gears through the discharge openings 21 and 22 in central plate 15 and outlet openings 27 and 28 in outer plate 26. The fluid passing through the openings 27 and 28 will enter the annular opening 54 and then will be forced out through chambers 59 and 57 into outlet nipple or connection 56. The provision of the relatively large driving gear 29 and the smaller driven gears 33 and 34 provides an improved means whereby an increased capacity will be provided in a relatively small compact pumping unit.

Referring now to Figure 13 there is disclosed a modified form of this invention wherein the driving gear 65 is the same diameter as the pair of driven gears 66, and each gear is formed with 20 teeth. The dot and dash line 67 indicates the effective circular area within which the pump may be disposed.

In Figure 14 the driving gear 68 is larger in diameter than the driven gears 69 and 68 and has 20 teeth, whereas gears 69 have 10 teeth. The pumping capacity of gears 68 and 69, however, is the same as the arrangement shown in Figure 13, but the circular area 70 of gears 68 and 69 is substantially less than circular area 67 of Figure 13.

In Figure 15 the driving gear 71 has 20 teeth and the three driven gears 72 have 10 teeth. The addition of a third driven gear increases the capacity of the pump by 50%.

In Figure 16 the capacity of the pump is increased 100% within the same effective area by arranging the driving gear 73 with four driven gears 74 and the driving gear 73 is formed with twice as many teeth as each driven gear.

In Figures 14, 15 and 16 the effective circular area of the gears is the same, but the variation in the number

of driven gears provides the desired increased pumping capacity. An outstanding feature of this unit is that the use of an enlarged driving gear with smaller driven gears will deliver more fluid than a unit comprised of equal diameter gears, the overall size of the units being identical. This feature will be clearly understood by a comparison of the Figure 13 with the Figures 14 to 16.

I do not mean to confine myself to the exact details of construction herein disclosed, but claim all variations falling within the purview of the appended claim.

What I claim is:

A gear pump comprising a housing having a cylindrical bore, a wall integral with said housing extending transversely of said bore at the inner end thereof, said wall having a central bore axially aligned with and substantially smaller than said cylindrical bore, said wall having spaced apart inlet ports extending therethrough, a tubular outlet fitting integrally attached to said housing, a shaft journaled in said central bore and extending into said cylindrical bore, a central plate having an axial bore and a pair of diametrically opposed bores each intersecting and overlapping said axial bore, a pump driving gear rotatably disposed in said axial bore in keyed relation to said shaft, a driven gear disposed in each of said pair of opposed bores with each meshing with said driving gear whereby to rotate therewith, a pair of outer plates engaging against opposite faces of said central plate with said plates mounted within the cylindrical bore in said housing, one of said outer plates engaging said wall and having a pair of transverse inlet openings therein aligned with the inlet ports in said wall on one side and with the unmeshing junctures of said driving and driven gears on the other side, the other of said outer plates having a pair of transverse outlet openings aligned with the meshing junctures of said driving and driven gears on the other side, said cylindrical bore in said housing having at the end thereof opposite said wall an annular recess terminating in an axially extending radially offset flange, a cylindrical end wall having inner and outer faces with said inner face in engagement with said second outer plate, a flange formed on the peripheral edge of said end wall adjacent said outer face, said end wall having a conduit formed on said inner face connecting said outlet openings in said second outer plate with said tubular outlet fitting, and a sealing ring positioned between the peripheral edge of said end wall and the base of said annular recess sealing said end wall to said housing.
